UNITED STATES PATENT OFFICE.

FRANCESCO CECCONI, OF WATERBURY, CONNECTICUT.

CORE-BREAKER.

1,246,877.

Specification of Letters Patent.

Patented Nov. 20, 1917.

Application filed July 12, 1917. Serial No. 180,069.

To all whom it may concern:

Be it known that I, FRANCESCO CECCONI, a subject of the King of Italy, residing at Waterbury, in the county of New Haven and State of Connecticut, have invented a new and useful Improvement in Core-Breakers; and I do hereby declare the following, when taken in connection with the accompanying drawings and the characters of reference marked thereon, to be a full, clear, and exact description of the same, and which said drawings constitute part of this application, and represent, in—

Figure 1 a plan view of a core breaker constructed in accordance with my invention shown with the cover removed.

Fig. 2 a sectional view on the line 2—2 of Fig. 1.

Fig. 3 a sectional view on the line 3—3 of Fig. 1.

Fig. 4 a view in rear elevation.

This invention relates to an improvement in core breakers adapted to break or disintegrate the core inside of a cast-metal tube. In the usual practice, these cast-metal tubes are rapped by hand with hammers to break or disintegrate the core so as to allow it to be poured out of the tube. The object of this invention is to provide a support for a cast-metal tube containing a core, and a series of hammers which will alternately rap the tube so as to break or disintegrate the core therein. A further object of the invention is to so inclose the mechanism that this operation may be performed without much noise as is necessarily the case when it is done by hand; and the invention consists in the construction hereinafter described and particularly recited in the claims.

In carrying out my invention, I employ a front frame 6 and a rear frame 7, the front frame formed with flanges 8 and 9 to which side walls 10 and 11 may be bolted, the walls being also bolted to the sides of the rear frame above which they project. The forward edge of the front frame is also provided with inwardly projecting flanges 12 and 13 to which a front wall 14 is bolted. The rear edges of the walls 10 and 11 project slightly beyond the rear frame 7, and between them is located a rear wall 15 which may be held in place by pins 16 inserted diagonally through the projecting ends of the side walls beyond the rear wall. The top of the front frame is provided with bearings for a driving shaft 17 which is provided at

one end with a fixed pulley 18 and a loose pulley 19 which will be driven by a belt, not shown. On the shaft 17 is a pinion 20 meshing with a large gear wheel 21 fixed to a tripping shaft 22 mounted in the front frame.

As herein shown, the front wall 14 is formed with a clearance opening 23 inclosed by a removable door 24 through which access may be had to the tripping shaft. This tripping shaft is formed with a series of radial passages 25, herein shown as eight in number, and at different angles, and in each of these openings is a tripper-arm 26 forked at its outer end in which is pivoted a roller 27. These arms each have a series of perforations 28, herein shown as three in number, through either one of which a key 29 may pass, the key extending through the shaft so as to interlock the arms therewith and so as to project from the shaft to the desired extent. These tripper-arms are respectively adapted to engage with, and lift a series of hammer-arms 30 which are formed from spring metal, these arms extending rearward onto the top of the rear frame 7 to which they are secured by means of plates 31 connected to the top 32 of the rear frame by bolts 33, the hammer-arms 34 being formed with longitudinal slots 35 through which the bolts extend thus permitting the longitudinal adjustment of the hammer-arms. Each of these arms has connected to it a hammer-head 36 in line with an anvil 37 which is mounted on a wood block 38 bolted to an anvil table 39. The anvil 36 is of trough shape, the edges 39 and 40 of which are notched in line with the hammers. It may be here noted that the side walls 10 and 11 are formed with clearance holes in line with the trough through which the tube 41 to be operated upon may be passed. As the tripping shaft is revolved, the tripping-arms successively engage with the under edges of the hammer-arms and raise the hammers above the anvil; and the continued movement of the tripping-arms carries them beyond the end of the hammer-arms and allows the hammers to descend and strike the tube resting upon the anvil, the spring of the metal of the hammer-arms being sufficient to strike a blow with necessary power to break or loosen the core within the tube. To provide for lifting the hammer-arms and hold them out of operative position, I provide a slide 42 which

is guided between the walls 10 and 11 by angle-irons 43, and this slide is connected to the upper ends of two pitmen 44 which are connected at their lower ends to levers 45 which are hung upon a rock-shaft 46 mounted in bearings 47 secured to the inner face of the side walls 10 and 11. These levers are offset at their outer ends to extend adjacent to the side walls which are formed 10 with segmental slots 53 through which handles 48 fixed to the ends of the levers 45 extend. The levers 45 are connected by a brace 49 so that both of the levers may be moved from either side. In the slide 42 are 15 a series of cushions 50 each of which rests upon a spring 51, these cushions being in line with the several hammer-arms and so as to be struck thereby by the downward movement of the hammers, the springs yielding to permit the hammers to strike the tube with sufficient force unless the levers 45 be turned so as to raise the slide, in which case 20 the cushions project so far above the anvil as to arrest the downward movement of the hammers before they come in contact with a tube on the anvil, thus providing for the introduction or removal of a tube. If greater power is required, the tripping-arms will be moved outward; or if less power, they 25 will be moved inward. In one case the hammer-arms will be raised to a greater extent so that the force of the blow will be increased; while in the other case, the hammers will be raised only slightly so that a light blow will be struck. The top of the 30 device will be closed by a sectional cover 52.

It will thus be seen that the mechanism is entirely inclosed so that the operation of hammering a tube to break or disintegrate 40 a core therein, may be accomplished without creating any material noise—a very valuable construction in metal work.

By providing a series of successively operating hammers, the core in the tube is 45 rapidly broken or disintegrated so that when a tube has passed through the machine the core may be readily poured out. With this machine the core in the long tube may be broken very rapidly. Thus a machine 50 with eight hammers may do the work of eight operators.

It will be understood that the machine is bolted or otherwise anchored to a floor so as to be sufficiently rigid to stand the necessary strain. Access to the interior of the 55 machine may be had through the rear support which is cut away for lightness and to provide a passageway through it.

I claim:

60 1. A core breaker comprising front and rear supports inclosed by walls, a series of hammer-arms connected with the rear support, a tripper-shaft mounted in the front support, means for driving the tripper-shaft, 65 a series of tripper-arms mounted in the trip-

per-shaft in line with the hammer-arms, hammers connected with the hammer-arms, and an anvil below the said hammers.

2. A core breaker comprising front and rear supports inclosed by walls, a series of hammer-arms connected with the rear support, a tripper-shaft mounted in the front support, means for driving the tripper-shaft, 70 a series of radially adjustable tripper-arms mounted in the tripper-shaft in line with the hammer-arms, hammers connected with the hammer-arms, and an anvil below the said hammers. 75

3. A core breaker comprising front and rear supports inclosed by walls, a series of 80 longitudinally adjustable hammer-arms connected with the rear support, a tripper-shaft mounted in the front support, means for driving the tripper-shaft, a series of tripper-arms mounted in the tripper-shaft in line 85 with the hammer-arms, hammers connected with the hammer-arms, and an anvil below the said hammers.

4. A core breaker comprising front and rear supports, an anvil located between them, hammer-arms, hammer-heads secured to the said hammer-arms in line with said anvil, a tripper-shaft mounted in the forward support, arms projecting radially from said tripper-shaft in line with said tripper-arms, means for rotating the tripper-shaft, 90 whereby the hammer-arms will be raised and allowed to drop, a transversely arranged vertically movable slide beneath said hammer-arms, and a series of spring-actuated cushions 95 mounted in said slide in line with said hammer-arms. 100

5. A core breaker comprising front and rear supports, an anvil located between them, hammer-arms, hammer-heads secured to the said hammer-arms in line with said anvil, a tripper-shaft mounted in the forward support, arms projecting radially from said tripper-shaft in line with said tripper-arms, means for rotating the tripper-shaft, 105 whereby the arms will be raised and allowed to drop, a transversely arranged vertically movable slide beneath said hammer-arms, a series of spring-actuated cushions mounted in said slide in line with said hammer-arms, 110 and levers connected with said slide and adapted to raise and lower the same. 115

6. A core breaker comprising front and rear supports, side walls connecting the front and rear supports, a front wall closing the front of the forward support and a removable wall closing the rear wall of the rear support, an anvil mounted between the front and rear supports adjacent to the front support, a tripper-shaft mounted in the 120 front support, means for rotating the tripper-shaft, radially adjustable tripper-arms mounted in said tripper-shaft, a series of 125 hammer-arms adjustably connected with the rear support and extending into line with 130

the tripper-arms, each of said hammer-arms provided with a hammer in line with the said anvil, a transversely arranged slide in rear of the anvil and below the hammer-arms, said slide carrying a series of spring cushions in line with the several hammer-arms, pitmen connected with said slide, levers connected with said pitmen, and a rock-shaft on which said levers are mounted,

said levers provided at their outer ends with 10 handles projecting through the side walls.

In testimony whereof, I have signed this specification in the presence of two subscribing witnesses.

FRANCESCO CECCONI.
